CLAIM

The ornamental design for a dispensing stand for a lavatory cleaning device, as shown and described.

DESCRIPTION

FIG. 1 is a front perspective view of the dispensing stand for a lavatory cleaning device showing my new design;

FIG. 2 is a front side elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines show portions of the design that form no part of the claimed design.
